UNITED STATES PATENT OFFICE.

CHARLES WILBUR MEGUIAR, OF SONORA, KENTUCKY.

DEVICE FOR MIXING AND KNEADING AMALGAM FROM MERCURY AND ALLOY.

1,329,843.

Specification of Letters Patent.

Patented Feb. 3, 1920.

Application filed February 8, 1917. Serial No. 147,510.

To all whom it may concern:

Be it known that I, CHARLES WILBUR MEGUIAR, a citizen of the United States, residing at Sonora, in the county of Hardin and

5 State of Kentucky, have invented certain new and useful Improvements in Devices for Mixing and Kneading Amalgam from Mercury and Alloy, of which the following is a specification, reference being had therein to

10 the accompanying drawing.

This invention relates to devices for mixing or kneading mercury and alloys to form an amalgam suitable for dental use.

The invention further relates to a novel 15 method of forming dental amalgam by a mixture of mercury and alloy.

In the formation of what are known as amalgam fillings for the use of dentists in filling tooth cavities, it is the practice to mix

20 mercury and dental alloy in what are considered proper relative proportions, and as mixed, to subject the mass to a kneading or mulling treatment until the mass attains the proper state or condition for packing the

25 same into the tooth cavity. Unless properly mixed or kneaded, an imperfect and unsatisfactory product oftentimes results, making impossible a proper filling for the preservation

30 of the treated tooth.

All prior methods of forming dental amalgams with which I am familiar have involved hand manipulation, and considerable guess-work on the part of the operator as to the character of treatment, duration of

35 treatment, etc., of the mercury and alloy, to obtain the desirable product and a resultant satisfactory filling. At best, the practice of mixing and kneading the mercury and alloy mass heretofore in vogue has been an

40 unnecessary time consuming and expensive proposition, involving considerable skill, care, and manipulation on the part of the operator to obtain a satisfactory amalgam.

That practice which is quite general, being accepted as the most satisfactory, is for the dentist to place in a mortar or the like, a quantity of mercury and alloy, and with the hand by the aid of a pestle, spatula or similar tool, mix, partially knead or spatulate

45 the same until he considers the inixture has attained the desirable consistency, when the product is properly kneaded or mulled to its final condition between the fingers of one hand and palm of the other.

50 Many objections have manifested themselves from the above practice, notably the un-

sanitary characteristics of treatment incident to hand manipulation, exposure of the mixture to contamination or impurities, the loss of time in the treatment, etc. It is a matter 60 of common knowledge that high grade alloys after exposure to air, because of the percentage of silver which becomes superficially oxidized or tarnished on exposure, have little affinity for mercury, especially if the 65 alloy is exposed to dust, dirt or other impurities, which would prevent a proper balance of the ingredients constituting the amalgam, and it is one of the objects of the present invention to make possible a proper, 70 thoroughly practical and entirely satisfactory amalgam, through the medium of means substantially automatic in operation, leaving the hands of the operator free for other uses, during the formation of the 75 amalgam.

It is a further object of the invention to obviate substantially altogether contact of the hands of the operator with the product during and after the formation of the amalgam, and to overcome to a large extent any possibility of dust, dirt or other foreign substances becoming associated with the material during the treatment thereof.

In the practice of the present invention, it 85 is proposed to place the alloy and mercury in a tubular container and to subject said container to rapid agitation and preferably lengthwise reciprocation, whereby the functions of mixing, kneading and mulling of the 90 amalgam to a finished state for application to the tooth is accomplished, and without the use of pestles, spatulas or the like, as well as without the usual final kneading in the hands of the operator.

95 Another feature of the invention resides in the provision of a novel and improved container or mixing tube for the mixture comprising the mercury and alloy, the container being of a character to, in the manipulation thereof not only properly mix the ingredients but completely form the amalgam ready for use.

Another feature of the invention includes novel and improved supporting means for 105 the mixing container, as well as novel and improved means for rapidly agitating said supporting frame and container.

The invention further includes means whereby the mixing tube or container may 110 be readily assembled in place on the supporting frame and means for preventing ac-

cidental displacement or removal of the tube in the operation of forming the amalgam from the tube contents.

The invention further includes means whereby the mixing tube or container may be readily assembled in place on the supporting frame and means for preventing accidental displacement or removal of the tube in the operation of forming the amalgam from the tube contents.

The invention further includes means whereby the amalgam as formed in the mixing tube may be readily removed therefrom, without the use of scrapers or the like, frequently resorted to in the methods of amalgamating at present in use.

Another object of the invention is to make possible accurate and uniform treatments of the mixture to form dental amalgam, and to this end means is provided for positively agitating the mixing container with its contents in a uniform manner.

The invention further resides in a novel method of forming dental amalgams from mercury and alloy, which may be characterized as a method wherein a given quantity of mercury and alloy are placed within a container and subjecting the container to violent and rapid agitation, thereby causing a repeated alternating momentive action of the material in the container.

The improved method may be further characterized as one wherein the mercury and alloy is placed within a container closed at opposite ends and subjected to rapid agitation in opposite directions lengthwise of the container to form a completed amalgam.

Other and further improvements and novel details in the construction and arrangement of the parts of the device as well as novel steps in the method employed, will be appreciated from the description to follow, which for a clear understanding of the invention should be considered in connection with the accompanying drawing which forms a part hereof, and wherein is disclosed for the purpose of illustration, a convenient and satisfactory embodiment of the apparatus which has been found to be entirely practical and useful in carrying out the method.

In the drawings:—

Figure 1 is a front elevation of the device with the operating parts inclosed.

Fig. 2 is a similar view with the front wall of the actuating mechanism removed, and the movable casing for the supporting mechanism for the mixing tube or container removed.

Fig. 3 is a vertical sectional view of the device complete.

Fig. 4 is a transverse section substantially on the line 4—4 of Fig. 3.

Fig. 5 is a transverse section substantially on the line 5—5 of Fig. 3.

With more particular reference to the drawings wherein like reference numerals refer to corresponding parts throughout the several views, 1 is a suitable background or support, which latter may take the form of an elongated wooden board adapted to be secured as by screws or bolts to a wall or the like, though in this connection, it is to be borne in mind that the parts to be presently described may be directly secured to a wall or the like. Removably mounted upon the support 1 as by screws 3 is a fixed supporting plate or frame 4 having outwardly projecting ends 5 and 6 adapted to support therebetween guide wires or rods 7. Having sleeved engagement with said rods 7, is a vertically movable slideable carrying frame 8 having offset ends 9 and 10 respectively which said ends are adapted to receive opposed supports 11 and 12 respectively. The support 11 conveniently comprises a disk-shaped member having an annular flange to overlie the upper end of the mixing tube to be presently described, a yieldable disk 13 of any suitable material 90 being inserted at the base of the pocket formed by said annular flange and to engage the upper edge of the mixing tube. The support 11 is provided with a stem 14 having threaded engagement with the recess in the offset flange 9 of the supporting frame 8, whereby the support 11 may be vertically adjusted at will to accommodate for variation in the lengths of the mixing tubes. The opposed support 12 conveniently has a central conical recess 12^a connecting with a laterally extending recess 12^b, the recess 12^a being adapted to form a seat for the lower conical end of the mixing tube to be described, and the laterally extending recess forming a guide which in one position of the support 12 will assist in the assembling of the mixing tube between the opposed supports 11 and 12. The support 12 also has a stem 15 having a threaded engagement with the wall surrounding an aperture in the offset part 10 of the support 8. The peripheries of the supports 11 and 12 are preferably roughened as illustrated more particularly in Fig. 2 whereby 115 to be readily engaged by the fingers of the operator and adjusted to proper position, and in order to maintain these parts in adjusted position against accidental displacement, a suitable retaining means is provided, which preferably takes the form of an elongated leaf spring member 16 having opposed arms 16^a and 16^b adapted to engage respectively said roughened peripheries of the opposed supports 11 and 12.

It is understood that the supporting frame 8 is adapted to be moved vertically, and it is desirable that when the machine is not in operation, said supporting frame be maintained in a predetermined position to facilitate

tate the application and removal of the mixing tube or container, and thereby to position the supporting frame and the container for observation when the movable casing for these parts to be described has been moved into open position. To accomplish this function, I preferably take advantage of a spiral spring or the like 17 secured at one end to the upper offset terminal 6 of the fixed support 4 and at its opposite end to an eye or the like 18 secured to the movable frame 8 adjacent the lower end thereof.

A suitable casing 18^a is adapted to overlie the carrying or supporting frame for the container and its associated parts, the opposite sides of said casing forming tongues 18^b adapted to slidably engage longitudinally extending recesses or grooves 18^c in the sides of the fixed support 4 and to be held by friction in adjusted positions. The said casing 18^a is conveniently provided with a suitable operating handle or the like 19, and the downward movement of the casing is preferably limited by a suitable abutment 20. When the casing is in contact with the abutment 20, the movable supporting or carrying frame for the container will be exposed, as will be obvious whereas when the casing is in closed position or against the base of a case 32 to be described, the parts will be effectively protected against the entrance of dust, etc.

Any convenient driving mechanism may be employed for imparting reciprocating movement to the carrying frame 8, it being desirable that this movement be an exceedingly rapid one to obtain the best results. In the illustrative embodiment of the invention herein, this driving means preferably takes the form of a pitman rod 21 eccentrically mounted as by a pin 22 to a fly wheel 23. The pitman rod 21 at its lower end has a sleeved engagement 24 with a stub shaft 25 projecting outwardly from a projection of the support 8 above the offset flange 9 of said support. The terminal of the threaded extension 14 of the upper support 11 for the container conveniently overlies the sleeved engagement between the pitman rod and the stub shaft whereby to prevent accidental separation of the pitman rod from said stub shaft and whereby also to prevent any accidental displacement or separation of the stub shaft itself. The counter balanced fly wheel 23 is adapted to be rotated in any desired manner and as illustrated the same is mounted upon a shaft 26 having a clutch member 27 and coupling sleeve 28 adapted for the reception of a co-operating clutch member 29 on the rotatable driven shaft of the ordinary dental engine, not necessary to illustrate in detail herein. The fly-wheel shaft is held in place in any desired manner as by lock nut 27^b.

The mixing tube or container proper is indicated at 30, the same preferably being formed of glass and of relatively small diameter. The upper end of the tube is open whereas the lower end is closed and takes a conical form as illustrated at 31. The inner surface of the tube preferably tapers from a point adjacent the upper open end thereof to its point of connection with the conical base.

It has been ascertained that by placing a proper proportional amount of mercury and alloy in a suitable container, and subjecting said container to rapid reciprocating movement, for instance, 1200 reciprocations per minute, the amalgam may be completely formed in a very short interval of time. This speed of course may be varied which in turn will vary the length of treatment. The movement of the receptacle will create a rapid momentive action in alternately opposite directions of the material which contacts with the end walls of the container. This movement will be with considerable force or momentum, thereby constantly reshaping the material and imparting thereto an action similar to, though considerably more accurate and effective than, the action between the usual pestle and mortar.

It has been ascertained that the peculiar shaping of the mixing tube 30, i. e., the tapered walls thereof and the conical base, will impart a wedging action on the material as it seeks the base of the container in the movement of the latter, thereby creating in a short interval of time the necessary kneading or mulling action on the material.

If desired, a suitable casing 32 may be provided to overlie the drive wheel 23, the said casing being removably attached as at 33 to the support 1 and having an aperture in its side wall for the reception of the drive shaft 26 and an aperture at its base to receive the pitman member 21.

The method and operation may briefly be reviewed as follows:

The casing 18^a having been lowered to expose the support 8, the operator adjusts the opposed supporting heads 11 and 12 to the length of the container to be placed therebetween, the lower support 12 being at this time positioned with the lateral recess 12^b arranged foremost. A proper proportion of mercury and alloy having been placed within the container, preferably by means of suitable measuring apparatus, such as illustrated and described in an application for Letters-Patent filed concurrently herewith, the upper end of the tube is placed into engagement with suitable yieldable closure 13 in the annular recess provided in the lower surface of the upper support 11 whereupon the lower conical end of the container is guided by the recess 12^b in the lower support 12 into engagement with the central 130

recess 12^a of said support. The said support 12 is then given a rotatable movement upward which, because of the threaded engagement 15 will elevate the support 12 and 5 coöperate with the upper support 11 to fixedly hold the container in place. This rotatable movement of the support 12 will also position the guiding recess 12^b rearmost, and because of the engagement with the 10 knurled periphery of the heads 11 and 12 by the spring member 16, these supporting members 11 and 12 will be fixed against accidental displacement. A suitable stop pin or the like on the lower head 12 may be 15 used to engage the side spring 16 to positively limit the rotatable movement thereof. Power having been imparted to the drive shaft 26 as by the engine shaft 29, said shaft 26 and the fly wheel 23 connected therewith 20 will be rotated at a high rate of speed whereby through the medium of the pitman rod 21, the supporting frame 8 and the container carried thereby will be rapidly reciprocated thereby imparting to the material within the 25 container rapid momentive action in alternately opposite directions. As the material seeks the base of the container, it will be wedged into a conical shape or mass and as the same engages the opposite end of the 30 container formed by the member 13, the mass will flatten to be again reshaped in the opposite movement thereof in the reciprocation of the container. The mass after thoroughly mixing it will be seen, will be 35 constantly changed in shape and kneaded to a final amalgamated condition to be placed in the cavity of the tooth. When the operation is complete, the lower supporting member 12 is rotated downward so as to 40 bring the recess 12^b foremost and so as to slightly lower the member 12 with the result that the lower end of the container may be readily released from the recess 12^a and 45 guide groove 12^b by a lateral movement and separated from the upper support by a lowering movement. By inverting the detached 50 receptacle 30 the amalgam will readily fall out of the open end of the tube, the tapering inner wall of the same assisting in the discharging action. Normally the casing 18^a will remain in elevated position.

If it is desired to brighten and improve the color of the amalgam, a slight quantity of alcohol may be placed into the mixing or 55 amalgamating tube 30, together with the measured quantity of alloy and mercury when under the action of the tube the alcohol being agitated with the other materials will clearly cleanse the same and give to the 60 product a brightened appearance.

What I claim is:—

1. A device for forming dental amalgam from alloy and mercury comprising an elongated tube adapted to receive the mercury

and alloy, said tube having a chamber of 65 relatively narrow cross section, and the inner surface of the tube being constructed to form a kneading surface, said tube being closed at its ends, and mechanical means for rapidly reciprocating the tube endwise, substantially as and for the purpose described. 70

2. An agitating device for forming amalgams from mercury and alloy comprising an elongated tube of small diameter having a conical closed end approximating a point, 75 whereby the inner surface of the tube constitutes a kneading surface, means for closing the opposite end thereof, and means for rapidly agitating said tube lengthwise whereby to mix and simultaneously knead 80 the material.

3. An agitating device for forming amalgams from mercury and alloy comprising an elongated movable tube having an integral closed lower end conical in shape, and an inner surface tapered inwardly from the upper end thereof to said conical end. 85

4. An amalgamating device for mercury and alloy comprising an elongated tube having a closed upper end, the inner wall of the 90 tube being tapered inwardly toward the lower closed end thereof, and means for rapidly reciprocating the tube.

5. An amalgamating device for mercury and alloy comprising an elongated tube having a conical lower end, means for closing 95 the upper end, and means for subjecting the tube to lengthwise reciprocatory movement at a high rate of speed whereby to mix and knead the material into an amalgam. 100

6. An amalgamating device of the character described comprising a reciprocating frame having opposed supporting heads, a tubular container supported between the heads, said container having a closed lower 105 end and an open upper end, the head having means to close the upper end, the inner surface of the container gradually approaching a point, and means for rapidly reciprocating said frame. 110

7. An amalgamating device of the character described comprising a reciprocating frame having opposed supporting heads, a tubular container supported between the heads, said container having a cone shaped 115 lower end, the lower supporting head having in its upper surface a central recess and a connecting groove leading to the periphery thereof to receive the cone-shaped end, and the upper head having means for closing 120 the upper end of the container.

8. An amalgamating device of the character described comprising a reciprocating frame having opposed supporting heads, a tubular container supported between the 125 heads, said container having a cone-shaped lower end, the lower supporting head having a central recess to receive the cone-

shaped end, and a laterally extending recess to guide said lower end of the tube into said seat.

9. An amalgamating device of the character described comprising a reciprocating frame having opposed supporting heads, a tubular container supported between the heads, said container having a cone-shaped lower end, the lower supporting head having 10 a central seat to receive the cone-shaped end, and a laterally extending recess to guide said lower end of the tube into said seat, said laterally extending recess being normally positioned foremost, and means 15 whereby said lower head may be rotated to reposition said lateral recess and bring the heads into holding engagement with the tube.

10. An amalgamating device of the character described comprising a reciprocating frame having opposed supporting heads, a tubular container supported between the heads, said container having a cone-shaped lower end, the lower supporting head having 20 a central recess to receive the cone-shaped end, and a laterally extending recess to guide said lower end of the tube into said seat, said laterally extending recess being normally positioned foremost, means whereby 25 said lower head may be rotated to reposition said lateral recess and bring the heads into holding engagement with the tube, and frictional holding means for the lower head to prevent accidental rotation.

30 11. In an amalgamating device of the character described, the combination of a reciprocating supporting frame having opposed heads, a tubular container to be positioned between the heads, said heads having screw threaded connection with the frame to permit of adjustment, and means preventing accidental rotation of the heads.

35 12. In an amalgamating device of the character described, the combination of a reciprocating supporting frame having opposed heads, a tubular container to be positioned between the heads, said heads having screw threaded connection with the frame to permit of adjustment, and means preventing accidental rotation of the heads comprising a spring member frictionally engaging both heads.

13. In an amalgamating device of the character described, the combination of a reciprocating supporting frame having opposed heads, a tubular container to be positioned between the heads, said container having a tapered wall constituting a kneading surface for the amalgam, and an inclosing casing for said frame and container. 55

14. In an amalgamating device of the character described, the combination of a supporting frame having vertically spaced forwardly extending supports, opposed heads to engage a container therebetween, 60 said heads having projections extending through apertures in the supports, a drive member, a pitman rod connected to said member, a stub shaft on the supporting frame above the upper head, said pitman 70 rod having sleeved engagement with the stub shaft and the projection on the upper head constituting retaining means for the lower end of said pitman rod.

15. In an amalgamating apparatus of the character described, the combination of a tubular container of small diameter having a closed lower end, means for supporting the container with the open end uppermost, closing means for the upper end of the container, and means for rapidly reciprocating said supporting means, said container having an inner surface which tapers from the open upper end thereof to the lower end which lower end assumes approximately a 85 pointed shape.

16. In an agitating amalgamating device the combination of a movable supporting frame comprising opposed supporting heads adapted to receive therebetween a container 90 for mercury and alloy or the like, the lower head having a threaded engagement with the frame whereby to be elevated into contact with the container, and the upper support having closing means for the container, 95 the lower head having a laterally extending guide groove adapted in one position of the head to be disposed foremost, and means for limiting the rotatable movement of said lower head. 100

In testimony whereof I hereunto affix my signature.

CHARLES WILBUR MEGUIAR.
